(57) **CLAIM**

The ornamental design for a frame for a ceiling light, as shown and described.

DESCRIPTION

FIG. 1 is a front perspective view of a frame for a ceiling light according to an embodiment;

FIG. 2 is a front view of the frame for a ceiling light of FIG. 1;

FIG. 3 is a rear view of the frame for a ceiling light of FIG. 1; FIG. 4 is a left side view of the frame for a ceiling light of FIG. 1;

FIG. 5 is a right side view of the frame for a ceiling light of FIG. 1;

FIG. 6 is a top view of the frame for a ceiling light of FIG. 1; FIG. 7 is a bottom view of the frame for a ceiling light of FIG. 1;

FIG. 8 is a cross-sectional front view of the frame for a ceiling light taken along line Viii-Viii of FIG. 1;

FIG. 9 is a cross-sectional front perspective view of the frame for a ceiling light taken along line Viii-Viii of FIG. 1; and, FIG. 10 is a front perspective view of the frame for a ceiling light of FIG. 1 shown in use coupled with a light.

The broken lines shown in FIG. 10 illustrating a light forms no part of the claimed design.
